[57] CLAIM

The ornamental design for a frame member for windows, as shown and described.

DESCRIPTION

FIG. 1 is a perspective view of a frame member for windows embodying my new design, shown fragmentarily to indicate indeterminate length.

FIG. 2 is a side elevation of the frame member of FIG. 1.

FIG. 3 is a side elevation of the opposite side of the frame member of FIG. 1.

FIG. 1.

FIG. 2.

FIG. 3.

UNITED STATES PATENT AND TRADEMARK OFFICE
CERTIFICATE OF CORRECTION

PATENT NO. : D-300,255

DATED : March 14, 1989

INVENTOR(S) : Dietrich F. Schmidt

It is certified that error appears in the above-identified patent and that said Letters Patent is hereby corrected as shown below:

Column 2, line 6 reads "member for windows" and should read
-- member for a window --.

Signed and Sealed this
Fourteenth Day of November, 1989

Attest:

JEFFREY M. SAMUELS

Attesting Officer

Acting Commissioner of Patents and Trademarks
